UNITED STATES PATENT OFFICE

JOSEPH BECKER, OF MONTCLAIR, NEW JERSEY

FOLDING CLOTHES HANGER

Application filed July 31, 1929. Serial No. 382,488.

This invention relates to garment supports and more particularly to a device known as a garment hanger and by means of which clothes may be suspended from a hook or other support.

At the present time it is customary to form a garment hanger with a body portion to extend transversely through the upper portion of the garment and this body portion is rigid throughout its length. Therefore, it is difficult to apply the hanger as it cannot be easily passed through the neck opening of a garment closed at the front and it is also difficult to remove it and, in fact, a garment made of light material is liable to be torn when applying or removing a rigid hanger.

Therefore, one object of the invention is to provide a hanger including a bar or body portion formed of companion sections or arms adapted to be moved from an extended position for use to a folded position and allow the hanger to be very easily put in place within a garment or removed.

Another object of the invention is to provide the hanger with a support-engaging element so formed that it may also serve as a latch by means of which the pivoted arms of the hanger may be securely but releasably retained in an extended position.

Another object of the invention is to so form the improved hanger that it will be very simple in its construction and allowed to be easily operated.

The invention is illustrated in the accompanying drawings, wherein

Figure 1 is a perspective view of the improved garment hanger,

Fig. 2 is a view showing the hanger in front elevation and by dotted lines indicating the manner in which it may be folded,

Fig. 3 is a fragmentary view taken on the line 3—3 of Fig. 2,

Fig. 4 is a sectional view taken transversely through the hanger on the line 4—4 of Fig. 3.

Fig. 5 is a perspective view showing the hanger folded, and

Fig. 6 is a fragmentary top plan view of a modified construction.

This improved garment hanger consists of a body portion formed of companion arms 1

and 2 and a support-engaging element or hook 3 adjustably carried by the inner end of one arm and adapted to engage the other arm in order to securely but releasably retain the arms in an extended position for use. The arms are preferably formed of wood, although other suitable material may be employed and are curved longitudinally in order that the body may properly conform to the upper portion of a garment when the hanger is in use. These arms have their inner ends overlapped and pivotally connected by a rivet 4. It will thus be seen that, while the arms are permanently connected, they may be folded, as indicated by dotted lines in Fig. 2, and thereby allowed to be easily passed through a small neck opening in a dress or other garment of a small child and then swung to an extended position. The support-engaging element 3 is formed of wire and has an upper portion or hook consisting of a strand bent to provide a bill 5 and shank 6. The lower portion of the shank is flattened, as shown at 7, and its inner face is notched to form a socket or seat 8.

The lower portion of the support-engaging element is also formed from a wire strand and this strand is bent to form a stem 9 rotatably received in a groove 10 formed in the inner end portion of the arm 1 although it could be formed in the arm 2. Arms 11 and 12 extend from the upper and lower ends of the stem 9 and from these arms project jaws 13 and 14 terminating in side extensions or fingers 15 and 16. These side extensions 15 and 16 are of sufficient length to extend across the upper and lower edge faces of the arms 1 and 2 and the extension 15 carries an upstanding post 17 to which the flattened lower end of the shank 6 is pivoted by a rivet or equivalent fastener 18. At the upper end of the post is formed a tooth 19 adapted to engage in the socket 8 and releasably retain the hook or upper portion of the support-engaging element in a raised position. Therefore, this hook may be disposed in a raised position when the hanger is in use and when the hanger is folded the hook may be swung downwardly to the position shown in Fig. 5. The lower portion of the support-

engaging element constitutes a clamp adapted to be swung from the position shown in Fig. 5 to the operative position shown in Fig. 1 in which the jaws 13 and 14 together with their extensions 15 and 16 extend across the upper and lower edge faces of the overlapped inner end portions of the two sections 1 and 2 and serve to securely but releasably hold the sections extended. In order to prevent movement of the jaws when swung toward an operative position, there has been provided pins 20 and 21 which project from the upper and lower edge faces of the two arms of the hanger and each of these pins consists of a short strand of wire having one end bent to project from the hanger arm and its other end bent to form a spur 22 driven into the arm. The intermediate portion 23 extends longitudinally of the arm and constitutes a wear-resisting element over which the jaw moves, as shown in Figs. 2 and 3. Therefore, the clamp will be prevented from cutting grooves in the upper and lower edge faces of the two arms 1 and 2.

25 When the improved garment hanger is in use, the support-engaging element is swung to the inoperative position shown in Fig. 5 with the hook extending upwardly and the hanger may be easily passed through the neck of a garment. The arms are then extended and the support-engaging element turned to the operative position. When so moved, the jaws extend across the upper and lower edge faces of the overlapped inner end portions of the two arms and retain them extended with the hook projecting upwardly for engagement with a support. When the hanger is to be removed, the support-engaging element is again turned to the releasing position and the arm 2 may be swung to a folded position and the hanger easily removed. If it is desired to pack the hanger in a suit case or place it in a bureau drawer without the hanger occupying a large amount 45 of space, it will be folded and the hook then swung downwardly out of the way.

In Figure 6, there has been shown a slightly modified construction. Referring to this figure, it will be seen that the two arms 24 and 25 have their inner end portions 26 and 27 reduced in thickness so that when they are overlapped and pivotally connected by a rivet 28, the side faces of the two sections will be flush. Therefore, the intermediate portion of the hanger will be of the same thickness as the remaining portions thereof.

Having thus described the invention, I claim:

1. A garment hanger comprising arms pivoted to each other for movement from an extended position to a folded position, and support-engaging means movably carried by one arm only and movable into and out of position to engage the other arm and retain the arms in an extended position.

2. A garment hanger comprising arms having their inner ends overlapped and pivotally mounted for swinging from an extended to a folded position, and a support-engaging element having a stem turnably mounted and provided with portions to engage the arms and retain the arms extended. 70

3. A garment hanger comprising arms having their inner ends overlapped and pivotally mounted for swinging from an extended to a folded position, and a support-engaging element having a stem rotatably received in a seat formed adjacent the inner end of one arm to turnably mount said element and bent to provide means for engaging the inner end portions of the arms and secure the arms extended. 75 80

4. A garment hanger comprising arms having their inner ends overlapped and pivotally mounted for swinging from an extended to a folded position, and a support-engaging element having a stem passed through a seat adjacent the inner end of one arm to turnably mount said element and bent above and below the said arm to provide extensions adapted to engage across the upper and lower faces of the inner end portions of the arms and secure the arms extended. 85 90

5. A garment hanger comprising arms having their inner ends overlapped and pivotally mounted for swinging from an extended to a folded position, and a support-engaging element having a stem passed through an opening adjacent the inner end of one arm to turnably mount said element and bent above and below the said arm to provide extensions adapted to engage across the upper and lower faces of the arms and retain the arms extended, and guards having portions extending longitudinally of the last-mentioned arm and provided with upstanding abutments to engage the extensions when moved to a securing position. 95 100 105

6. A garment hanger comprising arms having their inner end portions overlapped and pivotally connected, and a support-engaging element having a lower portion pivotally carried by one arm and formed with jaws to extend across upper and lower faces of the arms and secure the arms in a set position. 110 115

7. A garment hanger comprising arms having their inner end portions overlapped and pivotally connected, and a support-engaging element having a lower portion pivotally carried by one arm only and formed with jaws to extend across upper and lower edge faces of the arms and secure the arms in a set position. 120 125

In testimony whereof I affix my signature.

JOSEPH BECKER. [L. S.] 125
